AERIAL TARGET LAUNCHING TECHNIQUE

Leonard W. Seeley and William S. Roney, China Lake, and Lewis A. Stevens, Ridgecrest, Calif., and Reginald R. Vancil, Oceana, Va., assignors to the United States of America as represented by the Secretary of the Navy

Filed Nov. 10, 1955, Ser. No. 546,289

2 Claims. (Cl. 258—1.2)

(Granted under Title 35, U.S. Code (1952), sec. 266)

The invention described herein may be manufactured and used by or for the Government of the United States of America for governmental purposes without the payment of any royalties thereon or therefor.

This invention relates to methods and means for launching objects from the ground to be towed by aircraft and more particularly to methods and means for launching high speed aerial tow targets directly from the ground for towing by aircraft.

With the advent of high speed aircraft and guided missiles the evaluation of the controls of such guided missiles and of the fire control apparatus of such aircraft has become increasingly difficult. Similarly, realistic training of fighter pilots and aviation gunners has presented a problem. It has become necessary to substantially abandon the banner and sleeve type tow targets previously used because of the excessive drag and vulnerability to fluttering and tearing in high speed flight which is inherent in such tow targets. New targets, capable of high speed operation with stability of flight and resistance to breakage, have been developed and these new targets often take the form of comparatively heavy, lengthy objects, made of rigid components. One such target which has been particularly successfully used is the dart shaped assembly shown in the illustration of this invention and such an assembly is specifically disclosed and claimed in the copending United States patent application of Leonard W. Seeley, Serial Number 543,043, filed October 26, 1955, now U.S. Patent No. 2,821,396. Targets of such design may obviously be constructed of any chosen size, but for practical purposes are generally of adequate length to give good visibility and are, therefore, of substantial weight. For example, a dart shaped target twelve feet long and having other dimensions appropriate to such a length, weighs over one-hundred pounds when constructed of $\frac{3}{8}$ " plywood.

The two main methods of launching tow targets prior to this invention involved either dragging such targets from the ground or releasing them from the tow plane in the air. The dragging method invariably results in major damage to the target and this is particularly true when such rigid, lengthy, and heavy articles as the new high speed target constructions are involved. Storing such targets in tow planes for release in flight presents problems of stowage and of safety in separating the targets from the tow planes. This invention is predicated on the basic discovery that an object with a tow line attached thereto may be snatched from a stationary position on the ground by an aircraft in flight without dragging the object and with a minimum of forces applied thereto if the tow line is arranged for pick-up up-range from the object to be snatched rather than down-range of the object. It has been found that with such an arrangement, proper pilot technique will allow safe and damage-free pick-ups by aircraft flying at speeds considerably faster than one hundred miles per hour and that the initial movement of the object picked up is substantially

2

vertical when picked up in this manner so that there is no dragging of the object on the ground.

It is, therefore, an object of this invention to provide a method and means for launching objects from the ground for aerial towing, without damaging such objects or the towing aircraft.

It is a further and more specific object of this invention to provide a method and means for ground launching rigid high speed aerial tow targets for towing by an aircraft whereby the targets may be snatched from positions of rest on the ground by aircraft in flight without damage to either the aircraft or the targets.

Other objects and many of the attendant advantages of this invention will be readily appreciated as the same becomes better understood by reference to the following detailed description when considered in connection with the accompanying drawings wherein:

Fig. 1 is a schematic showing of the ground launching technique which is the subject of this invention, illustrating the required ground installation, the flight pattern of the aircraft, and the attitude of the tow line in various phases of the pick-up;

Fig. 2 is a fragmentary elevation of an aircraft suitably rigged with a towing hook for use in the technique depicted in Fig. 1;

Fig. 3 is an elevational view of a ground installation suitable for practice of this invention, showing details of the tow line, of the standards supporting the pick-up loop thereof for snatching by the aircraft, and of the means securing the object to be picked up in position for the pick-up.

Referring now to the drawings in which like reference numerals refer to like parts throughout, attention is particularly directed to Fig. 1, which schematically shows the operation of the entire technique. The novel concept on which the method of this invention depends is implemented by the physical arrangement of the necessary ground equipment so that the object to be picked up, as a tow target, is placed down-range from the standards which support the tow line for pick-up, so that the towing aircraft picks up the entire tow line before it passes over the target, as shown in Fig. 1.

The method can be employed by any aircraft, by the expedient of providing a hook which is supported beneath the fuselage and which is preferably releasable. Many such arrangements are obviously possible but one exemplary structure is illustrated in Fig. 2 to show how naval aircraft equipped with conventional retractable arresting gear hooks may be adapted for use in this method. In Fig. 2, aircraft 2 has the conventional tail hook 4 mounted on a yoke 6 which is attached to retracting means, not shown, operable from within the aircraft. Attached to yoke 6, by any suitable means is a gripping and release device 8 for releasably supporting a towing hook 16. In the illustrative example, device 8 is a conventional bomb rack of well known type, having clamp-type jaws 10, steady rest and release cam 12, and linkage means 14 operable from within the aircraft for opening of grips 10 when desired. Bomb rack 8 is not of the essence of this invention and therefore the details of the gripping jaws and of the release linkages are not given, it being obvious that any releasable holding means could be substituted. Towing hook 16 is provided with lugs 18 of a shape to be gripped or held by the jaws 10 and of such a length that the shaft of the towing hook 16 will be steadied by the rest 12.

The tow line structure, its relationship to the object to be picked up or snatched, and the ground equipment preferably used to facilitate pick-up or snatching of the article, are illustrated in Fig. 3, in which the tow line 20 is a suitable length of strong, flexible line. Both the na-

ture of the line 20 and the length thereof may be varied. It has been found that line lengths in the order of 1800 feet give good results and that longer tow lines are effective to compensate for poor pilot technique or to make possible the pick-up of larger loads. It has also been found that $\frac{5}{16}$ " nylon line is particularly well suited, by weight, drag characteristics and elasticity, for use in this method, although lines of other size and of material of suitable strength, weight and elasticity may obviously be used. Tow line 20 has swivel connectors 21, 22 at each of its ends and one of these swivel connectors 21 is connected to a pick-up loop 24 comprising 80 feet of line, while the connector 22 at the other end of the tow line is adapted to be connected to the object to be snatched, as for example a tow target 26, as illustrated.

The ground equipment used in this method comprises a pair of standards 28 each having a spring clip 30 adapted to releasably hold tow line loop 24, and a support 32 and stake 34 for positioning the object to be towed. Standards 28 are utilized as shown in perspective in inset I of Fig. 1, the loop 24 of the tow line 20 being stretched between the standards for pick-up by hook 16. The loop is supported on the down-range side of the standards by releasable spring clips 30 as shown in detail in Fig. 3. Support 32 and stake 34, shown in detail in Fig. 3, hold the object to be snatched in a preferred orientation for pick-up.

It is inherent in this new pick-up method that the object to be picked up, as tow target 26, has a tendency to be pulled up-range, prior to the pick-up, as the tow line is lifted by the towing aircraft. Such movement would result in unpredictable conditions and attitudes at the instant of pick-up and in possible damage to the tow target. This tendency is overcome by provision of stake means 34 suitably anchored in the ground and of a size to fit within an appropriate loop or eye element 35 which is provided on the object to be picked up. Thus, as may be seen from Fig. 3, stake 34 prevents horizontal movement of the tow target, but allows release of the target by vertical movement thereof. The positioning and support of the target is completed by use of supports 32 on either side of the target to engage portions thereof and maintain it substantially aligned with the proposed line of flight and out of contact with the ground for launching, as shown in Fig. 3.

The foregoing is a description of the equipment necessary to practice the novel method of this invention. The object to be towed is preferably provided with means to cooperate with stake 34 and with means for attachment to the tow line as described above. In the practice of this invention the object to be towed, as for example a tow target 26, is placed on an appropriate range area with its nose in the proposed direction of flight, with eyelet 35 thereof positioned on stake 34 and with surfaces thereof supported by supports 32, as shown in inset II of Fig. 1 and in Fig. 3. Tow line 20 is laid full length on the ground, on the up-range (direction of approach of the towing aircraft) side of the target, with the down-range end thereof being attached to the pivoted towing yoke 36 of the target by means of the swivel connection 22. Towing yoke 36 is pivoted substantially at the center of gravity as disclosed in the aforementioned U.S. Patent No. 2,821,396 which relates to the aerial tow target structure. The opposite (up-range) end of the tow line is attached, as by swivel connection 21, to the pick-up loop 24. Standards 28 are placed on either side of the line of flight in a position to receive and support loop 24 with a portion thereof stretched between the standards at an elevated point, as shown in Fig. 1 (inset I) and in Fig. 3, and the loop is releasably supported in the elevated position on the down-range side of the standards by spring clips 30. Preferably the standards 28 and target 26 are so placed that the tow line 20 may be loosely laid therebetween, with no tension and no coiling.

With the target and ground equipment arranged as described hereinabove, an aircraft 2, with towing hook 16 extended as shown in Fig. 2 is flown in the flight path illustrated by the line P over the imaginary ground pattern G, as shown in Fig. 1. The towing aircraft is flown over the pick-up standards 28 toward the target 26 at such an altitude that its towing hook 16 engages the towing loop 24. The aircraft then climbs steadily up (as shown in Fig. 1), over and beyond the target 26. As 10 the tow line lifts from the ground and the point of separation of the line from the ground approaches the target, the air load and inertia forces acting against the tow line shape it into what appears to be a modified catenary curve, as shown at K in Fig. 1. Since the only forces 15 which can be applied by the line to the target must be in the direction of the line, the forces applied by the line are such as to strongly lift or raise the target 26 upwardly into the air without dragging it, such motion freeing the target from stake 34 and supports 32 and launching it 20 for flight without damage. Because of the stretching of the tow line and the "cushioning" effect of the tow line catenary, the inertia forces on the target remain low.

At the end of the flight, the tow plane 2 flies over a designated drop area at an altitude of 600 to 800 feet 25 over the ground. Tow hook 26 is then released by the pilot by means best shown in Fig. 2, operation of the operating linkage 14 of bomb rack 8 opening jaws 10 to allow the hook to be cammed free of the jaws by tow line forces acting about the cam 12 as a fulcrum. The hook then drops to the ground with the tow line and target and all of these parts are recovered, when possible, for reuse.

The above description, in general terms, should be sufficient to illustrate the invention. However, an example 35 of specific speeds, altitudes and techniques is given herein to further assist in practice of the invention, and this example is based upon use of high speed jet aircraft. Referring to Fig. 1, an aircraft 2 is flown, as at A, in the pattern shown, with hook down, and wheels and flaps up, 40 at about 150 knots indicated air speed, 300 feet above the ground and approximately 2,500 feet abeam the pick-up point. Shortly after this, a slowly descending turn is initiated toward the pick-up course. At B, approximately 400 feet up-range of the pick-up standards, the aircraft 45 should be wings level, indicated air speed 150 knots, lined up on the course, and at or very near the final pick-up altitude. At approximately 100 feet from the pick-up standards, as represented by C, one-hundred percent power is achieved, and there must be no change in altitude from here to pick-up. The pick-up at D can be felt by the pilot; immediately afterward the airplane is 50 smoothly rotated to a climbing attitude in which the maximum safe rate of climb is developed. This attitude is held until an indicated air speed of 120 knots is reached at E, at which time the aircraft is smoothly nosed over to an attitude that will permit maintaining the altitude gained. Depending on temperature and variance in technique, the altitude gained will amount to some 1,000 to 55 1,600 feet. It is emphasized that any attempt to compensate for a high pass by being in a descent after passing C can be extremely dangerous and should be avoided. In the interest of safety, the towing aircraft should be ballasted so that its center of gravity is on the forward 60 65 limit.

It should be obvious from the above description that this invention provides a new means and method for launching objects to be towed by aircraft, said means and method being simple in arrangement and operation and resulting in launching free of the dangers of damage to the towed object or to the aircraft which are inherent in the known prior means and methods for accomplishing this function.

While only a single specific illustrative example of 70 equipment and technique has been specifically described

herein, it is obvious that many variations and modifications are possible in the light of the teachings of this disclosure. It is, accordingly, to be understood that the scope of the invention is not intended to be limited by the specific illustrative example described but rather by the scope and language of the appended claims.

What is claimed is :

1. The method of effecting aerial pickup of a grounded tow target without ground-dragging thereof, comprising the steps of: pointing said tow target down-range relative to the direction in which it is to be picked up and towed by a pickup aircraft; providing a tow line of sufficient length to impose thereon, when the tow line is entirely raised out of ground contact during pickup operation, airload and inertia forces of magnitude effective to lift said tow target without dragging effect; securing said tow line to said tow target at substantially the center of gravity thereof; extending said tow line uprange from said tow target; securing the up-range end of said tow line to a tow line loop; supporting a length of said tow line loop in position to be engaged by a pickup aircraft; restraining said tow target against the up-range displacement which tends to occur during the pickup operation; causing a pickup aircraft to fly down range toward said tow line loop; causing said aircraft to effect engagement of said loop; and causing said aircraft to climb up and over said tow target to raise the entire tow line out of ground contact and to effect lifting of said tow target.

2. A ground array of tow target apparatus for enabling

a tow target to be lifted without ground-dragging during pickup operation by a pickup aircraft, said ground array of tow target apparatus comprising: a tow target pointed down-range relative to the direction in which it is to be picked up and towed; a tow line extending up-range from said tow target; said tow line having a down-range end terminating at said target and an up-range end secured to a tow line loop; means securing said down-range end to the tow target at substantially the center of gravity thereof; a pair of pickup standards releasably supporting a length of said tow line loop above ground for engagement by the pickup aircraft; an eye element secured to said tow target at the fore end thereof; a ground-embedded stake extending upwardly through said eye element for restraining said tow target only against up-range displacement during said pickup operation; and said tow line having a length of the order of 1800 feet such that the airload and inertia forces acting thereagainst, during a pickup operation wherein the tow line is entirely raised out of ground contact as the pickup aircraft engages said tow line loop and climbs and flies over the tow target, are effective to lift said tow target without dragging effect.
